UNITED STATES PATENT OFFICE.

EVI W. CHRISTIE, OF SEWAREN, NEW JERSEY, ASSIGNOR TO WHEELER CONDENSER AND ENGINEERING COMPANY, OF CARTERET, NEW JERSEY, A CORPORATION OF NEW JERSEY.

CONDENSING APPARATUS.

1,323,013.

Specification of Letters Patent. Patented Nov. 25, 1919.

Application filed February 20, 1917. Serial No. 149,721.

To all whom it may concern:

Be it known that I, EVI W. CHRISTIE, a citizen of the United States, residing at Sewaren, in the county of Middlesex and State of New Jersey, have invented an Improvement in Condensing Apparatus, of which the following is a specification.

This invention relates to a condensing apparatus, and particularly to an apparatus for condensing steam, but as will be understood is not necessarily so limited. The invention furthermore relates to an apparatus in the use of which the principle is utilized of transferring the latent heat of steam, or other vapor to be condensed, through a relatively thin wall, preferably of metal, to a layer or film of water or other liquid on the opposite surface of the wall, and passing a current of air over the layer or film of liquid, raising its temperature, and saturating the air with the liquid vapor which is carried away by the same, whereby a sufficiently low temperature is maintained on the said opposite surface of the wall to cause the transfer of the latent heat in the steam, or other vapor to be condensed. Consequently the same purpose is accomplished in the use of the invention herein set forth as is now done in ordinary steam condenser practice, by transferring heat from the steam to a body of circulating cooling water and then re-transferring the heat from the water to the atmosphere by passing the water over a cooling tower.

In carrying out my present invention therefore, I provide a condenser which may comprise a shell having a plurality of tubes placed in vertical positions therein and against the outer surface of which the steam or other vapor to be condensed is brought into contact, while at the upper end each tube is provided with means for admitting thereto an annular stream of water so as to initially cover the inner surface of the tube in a thin layer or film, in order that by the action of gravity this film may normally descend in contact with the inner surface of the tube to which it is supplied; and at the bottom of the condenser tubes I employ means for creating and passing through the same a draft of air, which, as will be under-

stood, has its temperature raised and becomes saturated with water vapor, taken up from the film of water, so that by this application of the principle of evaporation the temperature on the inner surface of the tube is maintained sufficiently low to cause the transfer of the latent heat from the steam directed against the outer surface of the tubes. Theoretically the amount of cooling water equals pound for pound the steam condensed, and under theoretical conditions, the entire film of water in each tube will be evaporated at the end of its travel therethrough, but as will be understood in practice there is likely to be an excess of water which will escape at the bottom of the tubes. In order to provide for this I may employ a suitable pump for reconveying such excess water to the reservoir at the top of the condenser to which the cooling water is originally supplied. I may also employ a suitable air pump with connections therefrom to the interior of the condenser shell for maintaining a vacuum therein, and the degree of vacuum maintained in the use of the condenser herein described depends upon the temperature of the cooling water employed, and also the temperature and degree of the humidity of the air passed through the tubes and over the cooling water so that under similar conditions of water and air temperatures the apparatus should give the same results in this respect as in ordinary condenser practice.

85

One form of condenser in which my present invention may be incorporated is illustrated in the drawing, in which:

Figure 1 is a central vertical cross section and partial elevation illustrating this condenser and the apparatus which may be used in connection therewith.

Fig. 2 is a partial plan on an enlarged scale of the end of one of the condenser tubes and the pipe employed in conjunction therewith, while

Fig. 3 is a partial longitudinal section of the upper end of one of the condenser tubes and the pipe employed in conjunction therewith.

Referring to the drawing it will be seen that in carrying out my invention I may em-

100

ploy a condenser shell 10 made in the usual manner, and as is customary, provided at its opposite ends with tube plates 11 and 12, fitted in and extending between which and 5 lying within the shell of the condenser there is a plurality of condenser tubes 13. The condenser shell and tube plates and parts associated therewith may be connected in any customary or desired manner and the 10 apparatus may be mounted upon suitable supports 14 or otherwise.

The condenser is provided with a steam inlet nozzle 15 and with an outlet 16 for the air and water of condensation, it being understood that the steam inlet 15 is connected with the exhaust from a prime mover, while the outlet 16, as illustrated, can be connected by a pipe 17 with an air pump 18 to create and maintain a vacuum within the shell of 20 the condenser.

It will be noted that in carrying out this invention in the form illustrated, it is necessary to fit the condenser with the tubes in a vertical position, and at the upper end of 25 the condenser the same is provided with a reservoir 19 in which there is a water supply inlet 20 connected by a supply pipe 21 with any suitable source for supplying the cooling water. The upper end of each condenser tube 13 is provided with a relatively short pipe 22 of appreciably smaller outer diameter than the inner diameter of the tube to which it is fitted. These short pipes 22 may be placed in position concentrically 30 with the condenser tubes in any desired manner. As illustrated, I have shown the upper ends of the condenser tubes provided with lugs or projections 23 for supporting the short pipes 22 which extend through a 35 plate 24 fitted in the reservoir for centering and maintaining the short pipes in position. The object of employing these pipes is to feed the cooling water to the interior of each condenser tube in the form of an annular wall, leaving space for air to pass 40 through the tube in the opposite direction.

At the lower end of the condenser, and suitably mounted and secured thereto, I employ an air box member 25. This is preferably in the form of an elbow, one end of 45 which is attached to the condenser, while at the other end it is provided with a fan or blower 26 mounted on a shaft 27 which is journaled at one end in a bearing 28 provided therefor in the walls of the water box, and adjacent the other end in bearing 29 mounted on a bracket 30 suitably connected to the air box 25. On this end of the shaft 50 27 a pulley 31 is mounted for turning the shaft and driving the fan. The air box 25 in the lower and undermost part thereof is provided with a discharge nozzle 32 from which the pipe 33 leads to the suction of a pump 34, the discharge from which by a 55 pipe 35 is connected to the reservoir 19.

In the use of this apparatus, as may be gathered from the foregoing description, the cooling water is supplied to the reservoir 19 through the pipe 21 from any suitable source, and by means of the short pipes 22 is fed to the interior of the condenser tubes in a film covering the inner surfaces thereof so that in this form by the action of gravity the cooling water descends through the condenser tubes, while by means of the fan 26, 70 the current of air is passed through the tubes over the surface of this cooling water in the opposite direction so that by evaporation the air becomes laden with the water vapor, and has its temperature raised and 75 escapes with the water vapor through the short pipes 22, it being understood that the water level in the reservoir is not permitted to reach the top of the short pipes so that the water cannot overflow into and pass 80 through the same.

It will be furthermore understood that as herein shown and described, this invention is particularly applicable to condensing steam, but that its use is not so limited, as 85 it may be used for other purposes, for example, in evaporating apparatus where the present practice is to have the tubes in the calandria filled with liquid and the liquid boiled by the application of steam on the 90 other side of the tubes. As will be apparent these tubes can be readily changed to film evaporators by merely inserting the tubes in the upper end of the heating surface which would also eliminate any tendency to prime over from one vessel to another. 95

I claim as my invention.

1. A condensing apparatus comprising a shell, a plurality of condenser tubes mounted therein, an open reservoir at the top of the condenser shell, a spacer plate in the reservoir, a plurality of relatively short pipes each spaced at its upper end in the said plate and extending at its lower end into a condenser tube, a plurality of lugs in the upper end of each condenser tube for receiving, centering, and supporting the short pipe that extends into the same so as to provide a uniformly annular passage between the condenser tube and the short pipe, and means for passing a current of air upwardly through the said condenser tubes and pipes and into the reservoir at the top of the condenser so that it may escape to the atmosphere. 115

2. A condensing apparatus comprising a shell, a plurality of condenser tubes mounted therein, an open reservoir at the top of the condenser shell, a spacer plate in the reservoir, a plurality of relatively short pipes each spaced at its upper end in the said plate and extending at its lower end into a condenser tube, a plurality of lugs in the upper end of each condenser tube for 120 125 130

receiving, centering, and supporting the short pipe that extends into the same so as to provide a uniformly annular passage between the condenser tube and the short pipe,
5 a curved box at the lower end of the condenser, a blower associated with the said box for creating a current of the air to be passed through the condenser tubes and short pipes, and a connection from the said box to the said reservoir for conveying from the 10 box to the reservoir any water which may reach the box from the condenser tubes.

Signed by me this 14 day of February, 1917.

EVI W. CHRISTIE.
